UNITED STATES PATENT OFFICE.

ALBERT H. OSTBERG, OF AURORA, ILLINOIS.

SAFETY DEVICE FOR JACKS.

1,289,241.

Specification of Letters Patent. Patented Dec. 31, 1918.

Application filed June 14, 1915. Serial No. 34,030.

To all whom it may concern:

Be it known that I, ALBERT H. OSTBERG, a citizen of the United States, residing at Aurora, in the county of Kane and State of Illinois, have invented certain new and useful Improvements in Safety Devices for Jacks, of which the following is a specification.

This invention relates to a safety stop for jacks, or the like, and the purpose of the invention is to provide an improvement in jacks whereby they may be operated with increased safety and efficiency.

In jacks such as are commonly employed for lifting purposes, the standard which supports the object to be lifted is slidably mounted in a frame and projected upwardly or downwardly by suitable operating mechanism. The principal object of this invention is to provide means for limiting the movement of the standard in the frame. A further object is to provide means for limiting the upward movement of the jack, whereby the projection thereof from its seat and other disastrous results are prevented. Another object is to provide a detachable safety stop. Still another object is to provide a safety stop which will limit the movement of the standard in one direction, 30 while freely permitting movement thereof in the reverse direction.

These and other objects of the invention will appear more fully in the following specification, taken in connection with the accompanying drawings, in which one embodiment and one application of the invention are illustrated.

In the drawings—

Figure 1 is a vertical section through a jack provided with my improvement, taken on the line 1—1 of Fig. 3.

Fig. 2 is a side elevation of an improved key for preventing rotation of the standard of the jack.

Fig. 3 is a horizontal sectional view taken on a plane passing through the line 3—3 of Fig. 1.

Fig. 4 is a fragmentary side elevation of the jack, showing a portion thereof in section on the line 4—4 of Fig. 3.

Fig. 5 is a perspective view of one of the stops or detent members; and

Fig. 6 is a side elevation of a detent guide and retaining member.

In the drawings the jack in which my improvements are embodied is shown as

comprising a frame or body 10, the lower portion of which is enlarged to form a housing for suitable operating mechanism, and the upper portion 11 of which is in the form 60 of a vertically-extending sleeve having a cylindrical bore therethrough which is closely fitted by the slidably mounted standard 12. This standard is provided with an enlarged head 13 at its upper extremity, which is 65 adapted to engage the object to be lifted, and when said standard is in its lowermost position the enlarged head is adapted to seat upon an annular flange 14, formed at the upper extremity of the portion 11 of 70 the frame. The standard 12 is provided on its outer side with a vertically-extending groove or key-way 15, which extends downwardly from the enlarged head 13 to the lower extremity of the standard. A key 16 75 closely fits the key-way 15 in the standard, and has formed integrally therewith a stud 17 which extends through and closely fits an aperture 18 in the sleeve 11 to be engaged by a nut 19, which coacts with a boss 20 80 formed in the outer side of the sleeve, whereby the key is held in fixed position with respect to the body or frame. It will be understood that the key is placed in position with respect to the frame before the standard 12 85 is lowered into position within the sleeve 11. By means of the construction just described, the standard is permitted to slide vertically, but is prevented from rotating with respect to the frame.

The standard 12 is further provided with an axial bore, the upper part of which is enlarged, as shown at 21, and the lower portion of which is provided with screw threads 95 adapted to engage a screw-threaded driving spindle 22. This spindle is provided, at the lower extremity of the threaded portion thereof, with an integrally-formed collar 23, which seats upon a bevel gear 24 mounted upon the cylindrical bearing portion 25 of the spindle. The bevel gear 24 is secured to the portion 25 by means of a key 26. The downward thrust of the spindle 22 is received by a suitable thrust-bearing carried by a lower cover or cap member 27, which threadedly engages the inner walls of the body or frame, and which is provided with an annular flange 28 adapted to seat against the lower annular surface of the frame.

The cap member 27 is provided with an internal chamber 29, which extends downwardly from the top thereof concentrically

with the axis of the spindle 22. A collar 30 seats on the lower wall of this chamber and rotatably engages the portion 25 of the spindle. The cap member is provided, upwardly of the collar 30, with an annular flange 31, which serves to retain the balls 32 against radial movement in an outward direction. These balls seat upon the collar, and are prevented from moving inwardly 10 by the loosely mounted sleeve 33, which rests upon the collar 30. These parts are so proportioned that the upper portions of the balls 32 extend beyond the upper surfaces of the cap member 27 and sleeve 33, and seated upon the balls is a second collar 35, which also closely engages the portion 25 of the spindle, and which forms a seat for the lower plane surface of the bevel gear 24.

20 The bevel gear 24 and spindle 22 are actuated by a bevel pinion 36, carried by a horizontally-operated shaft 37, having a projecting portion 38 adapted to be engaged by a suitable operating means or source of power. The standard 12 is cut away at 12^a to provide clearance for the bevel pinion 36. The horizontal shaft 37 is journaled in a hub 39, carried by a cap member 40, which closes the opening in the laterally-extending 25 projection 41 of the frame 10, being secured thereto by suitable pins 42 and the bolts 43 and nuts 44. It will be apparent that upon rotation of the horizontal operating shaft 37, the bevel gear 24 and spindle 22 will be 30 actuated, and thereby move the standard 12 upwardly or downwardly in the frame, according to the direction of rotation of the shaft 37. As the standard 12 moves upwardly in the frame, the downward thrust 35 thereof will be received by the thrust-bearing 40 previously described.

It will be apparent that unless suitable preventive means be provided, the continued operation of the shaft 37 in the 45 proper direction, and the corresponding rotation of the spindle 22, would project the standard 12 upwardly out of the sleeve 11 of the frame, which would probably result in breakage of parts of the jack, injury to 50 the object being lifted thereby, or other serious consequences.

For the purpose of preventing such result, I have provided an improved safety stop which automatically limits the upward 55 travel of the standard. The sleeve portion 11 of the body or frame is provided, adjacent the annular flange 14, with two diametrically opposite bosses 45, which are provided with alining apertures 46 there-through, adapted to be closely fitted by the stop guide and retaining members 47. These guide members are provided with annular flanges 48, which closely engage the outer plane surfaces 45^a of the bosses 45, 60 and the inner extremities of the members 47

have arcuate inner end surfaces concentric with the standard 12, but terminating outwardly therefrom, as shown in Figs. 3 and 4. Each of the guide members 47 is provided with a transversely-extending lug 50, 70 which seats upon a boss 51 formed on the sleeve 11. Studs 52 engage the lugs 50 and bosses 51, and thereby secure the guide members 47 in place with respect to the frame. Each guide member is provided with a rectangular radially-extending chamber or guideway 54, which is closely fitted by a slidably mounted detent or stop member 55. A coil spring 56 is mounted in each of the chambers 54 outwardly of the detent 55, 80 and serves normally to project the same inwardly into the bore of the sleeve 11.

The outer cylindrical surface of the standard 12 serves normally to prevent the detent members 55 from being projected inwardly, but when the standard has reached the desired upper limit of its travel, the detent members are automatically projected inwardly to engage the parallel transverse grooves 58, which are provided in the standard adjacent its lower extremity. These grooves are provided with lower radially-extending surfaces 59, which preferably lie in the same radial plane, and with upper outwardly inclined surfaces 60, which are 95 adapted to coact with the correspondingly inclined surfaces 61 formed on the detent members 55. It will be apparent that when the standard 12 has moved upwardly until the grooves 58 register with the guide-ways 100 54, the detent members 55 will be automatically projected inwardly to engage said grooves and thereby prevent further upward movement of the standard, owing to the engagement of the stops 55 with the 105 surfaces 59. The guide members 47 are formed to fit closely the apertures 46, so that the thrusts received from the standard are transmitted directly to the frame, instead of through the studs 52, which serve 110 as fastening means. Upon the reverse operation of the spindle 22, however, the inclined surface 60 will coact with the inclined surfaces 61 on the detent members, thereby forcing the detent members outwardly in the guide-ways 54 against the compression of the springs 56, and permitting the standard 12 to be lowered.

It will be apparent that the downward movement of the standard will be limited by 120 the contact of the enlarged head 13 with the annular flange 14 on the frame. If desired, my improved automatic stop may be suitably applied for limiting the downward movement of the standard. It will be observed that the detent members are diametrically opposed, and they are preferably arranged to engage the standard simultaneously, so that the further upward movement of the standard will be resisted at diamet- 125 130

rically opposite points, thus preventing twisting and bending strains upon the standard and spindle, or other parts of the device. The detent members are preferably 5 so located as to lie in a plane at right angles to a radial plane passing through the key-way 15, and it will be observed that the detenting devices and the key 16 are so arranged as not to interfere with the handle 10^a on the frame, which serves as a means for transporting the jack, or with the cut away portion 12^a of the standard.

A great advantage of my improved stop is that it operates automatically to limit the 15 upward movement of the standard, or to permit the reverse movement of the standard thereafter, and it will be apparent that if any of the parts of the stop become worn or impaired by use, the guide members 47 20 may be readily removed by detaching the studs 52, after which the worn or impaired parts can be easily repaired or replaced.

Another important advantage of my improved stop is that it may be readily applied 25 to jacks already constructed without great or costly alterations thereof, by providing the spindle of the jack with suitable depressions or grooves and the walls of the frame with suitable apertures to be engaged by 30 the guide members.

Although I have shown and described a particular embodiment of the invention, and have explained its application in connection with a particular form of jack, it 35 will be understood that my improved stop may be applied to various forms of jacks, or the like, and may itself partake of widely different forms and arrangements of parts without departing from the scope of my invention as defined in the appended claims.

I claim:—

1. The combination with the movable standard of a jack, of a spring pressed detent for limiting the upward movement 45 thereof, a detachable guiding housing for said detent, a cylindrical plug at one end of said housing, a flange intermediate the ends of said housing, and a securing lug depending from said flange.

50 2. The combination with the movable

standard and frame of a jack, of a detachable stop housing and guide member comprising a cylindrical plug adapted to fit an aperture in said frame adjacent said movable standard, said plug having an arcuate 55 surface on one end thereof concentric with the adjacent surface of said movable standard, an annular flange extending around the other end of said plug and adapted to engage the outer wall of said frame to maintain said plug in position in said aperture with its arcuate shaped end spaced slightly outwardly from said standard and from the inner wall of said frame, a lug depending from said flange, securing means for engaging 60 said lug, and a recess in said housing extending on both sides of said flange.

3. The combination with the movable standard and frame of a jack, of a detachable stop housing and guide member comprising 65 a plug adapted to fit an aperture in said frame adjacent said movable standard, said plug having an arcuate surface on one end thereof concentric with the adjacent surface of said movable standard, an annular flange extending around the other end of said plug and adapted to engage the outer wall of said frame to maintain said plug in position in said aperture, a lug 70 depending from said flange, securing means 75 for engaging said lug, and a recess in said housing extending on both sides of said flange.

4. A device of the class described, comprising a housing provided with a nipple 85 at one end, a flange adjacent the inner end of said nipple, a recess in said housing extending on both sides of said flange, a spring and a detent in said housing, and a securing lug depending from said flange and provided with an aperture for the reception of 90 fastening means, all of said elements constituting a unitary structure bodily attachable to and detachable from the frame of a jack.

In testimony whereof, I have subscribed 95 my name.

ALBERT H. OSTBERG.
